(57) **CLAIM**

The ornamental design for a guardrail support clamp, as shown and described.

DESCRIPTION

A portion of this document contains material subject to copyright protection. The copyright owner has no objection to the facsimile reproduction by anyone of the patent document or the patent disclosure, as it appears in the Patent and Trademark Office patent files or records, but otherwise reserves all copyrights whatsoever. The following notice applies to this document: Copyright © 2020, Hilmerson Safety Services, Inc.

FIG. 1 is a top front perspective view of a guardrail support clamp incorporating the claimed design.

FIG. 2 is bottom front perspective view of the clamp.

FIG. 3 is top back perspective view of the clamp.

FIG. 4 is a bottom back perspective view of the clamp.

FIG. 5 is a right side view the clamp.

FIG. 6 is a left side view of the clamp.

FIG. 7 is a back view the clamp

FIG. 8 is a front view of the clamp.

FIG. 9 is bottom view of the clamp; and,

FIG. 10 is a top view of the clamp.

The broken lines in the drawings depict environment or structural features that form no part of the claimed design. The shade lines in the drawings show contour and not surface ornamentation.

1 Claim, 5 Drawing Sheets
